(57) **CLAIM**

The ornamental design for a display screen of a communications device with a graphical user interface, as shown and described.

DESCRIPTION

FIG. 1 is a front view of a display screen of a communications device with a graphical user interface showing our new design; and,

FIG. 2 is a front view thereof, shown in the context of different environment.

The broken line showings of the display screen of a communications device in FIGS. 1-2 and the images, text and other elements of the graphical user interface in FIG. 2 are included for the purpose of illustrating environmental structure and portions of the display screen of a communications device with a graphical user interface. The broken lines form no part of the claimed design.
